(57) **CLAIM**

The ornamental design for an instrument unit, as shown and described.

DESCRIPTION

FIG. 1 is a top left side perspective view of an instrument unit showing my new design;

FIG. 2 is a front elevational view thereof;

FIG. 3 is a rear elevational view thereof;

FIG. 4 is an enlarged left side elevational view thereof;

FIG. 5 is an enlarged right side elevational view thereof;

FIG. 6 is a top plan view thereof; and,

FIG. 7 is a bottom plan view thereof.

The broken lines showing the tip in FIGS. 1-4 and 6-7 depict environmental structure that forms no part of the claimed design. All other broken lines depict portions of the instrument unit that form no part of the claimed design.

1 Claim, 3 Drawing Sheets
